SUPPORTING FRAME FOR A BIRD HOUSE OR THE LIKE

Donald T. Linkous, Columbus, Ohio

Application August 5, 1959, Serial No. 57,074

Term of patent 14 years

(Cl. D31—2)

Fig. 1 is a perspective view of a supporting frame for a bird house or the like showing my new design;
Fig. 2 is a front elevational view thereof;
Fig. 3 is a side elevational view thereof; and
Fig. 4 is a bottom plan view thereof.
The bird house shown in broken lines is for illustrative purposes only.

I claim:

The ornamental design for a supporting frame for a bird house or the like, substantially as shown and described.
